INVENTOR
Harold Rowntree
BY his ATTORNEYS Danby Shanks

UNITED STATES PATENT OFFICE.

HAROLD ROWNTREE, OF PASS CHRISTIAN, MISSISSIPPI, ASSIGNOR TO NATIONAL PNEUMATIC COMPANY, OF NEW YORK, N. Y., A CORPORATION OF WEST VIRGINIA.

UNIT-DOOR-CONTROL MECHANISM.

Application filed June 4, 1921. Serial No. 475,139.

To all whom it may concern:

Be it known that I, HAROLD ROWNTREE, a citizen of the United States, residing at Pass Christian, county of Harrison, State of Mississippi, have made a certain new and useful invention in Unit-Door-Control Mechanism, of which the following is a specification.

This invention relates to unit door control mechanism for street, railway and other car systems.

The object of the invention is to provide a door operating and control mechanism for street railway and other cars which is simple and economical to construct and install and efficient in operation.

A further object is to provide an operating and control mechanism of the nature referred to, which, while capable of installation and use upon individual street railway and other cars generally, is especially applicable to trains of cars rather than to cars which are operated singly.

A further object is to provide a door operating and control mechanism which effects power actuation of the doors towards closed position but which permits the doors to be individually operated manually towards open position.

A further object is to provide power actuated means common to a plurality of doors to effect the closure actuation of the doors but which permits any individual door to be disconnected from its power actuating means in case the door, in closing, encounters an obstruction to its closing movement, or in case it is desired to move the door towards its open position, and wherein, in addition, the door is again connected to its power actuating means when the obstruction has been removed.

It is also among the objects and purposes of my invention to include the door locking and the signalling means, and the means to disconnect the doors from their actuating mechanism, with an operating and controlling system set forth.

Other objects of the invention will appear more fully hereinafter.

The invention consists substantially in the construction, combination, location and relative arrangement of parts, all as will be

more fully hereinafter set forth, as shown in the accompanying drawings, and finally pointed out in the appended claims.

55

Referring to the drawings,—

Fig. 1 is a view in diagrammatic plan, indicating an arrangement of power actuated means for operating all the doors on each side of a car towards their closed positions 60 suitable for use in carrying out my invention.

Fig. 2 is a broken view in side elevation, parts in section, showing a power actuated door operating and control mechanism embodying my invention as applied to a door.

Fig. 3 is a broken view in section on the line 3, 3; Fig. 2, looking in the direction of the arrows.

Fig. 4 is a similar view on the line 4, 4, 70 Fig. 2, looking in the direction of the arrows.

Fig. 5 is a broken detail view showing a door lock and signal control arrangement employed in connection with my invention. 75

Fig. 6 is a view in elevation of a modification of the door control apparatus.

The same part is designated by the same reference numeral wherever it occurs throughout the several views.

80

According to the practice now most generally followed in train door operation a separate operating motor is provided for each door on each car, and, sometimes, separate door opening and closing motors are 85 employed for each door, each door operating motor having its own control mechanism. This practice involves a very great installation and equipment expense, not only in the construction and equipment of new 90 cars but in converting old cars. When the art advanced to multiple unit control of the door operations the desired multiple unit control was accomplished by methods of control of the door operating motors, 95 still retaining the feature of a separate door actuating motor, or motors, for each door.

It is among the special purposes of my present invention to provide a single motor for actuating all the doors on both sides of each car, and means cooperating with the motor actuated mechanism whereby any individual door may be readily and easily disconnected from the motor actuated mecha-

100

nism so as to be free to be moved manually. In accordance with my invention the single motor on each car drives suitable connections which effect only the closing movements of the doors, but when any particular door is disconnected from the actuating mechanism that particular door may be easily and readily moved by hand to open position. In other words, it is contemplated by my invention that each door be opened individually by the passengers, either from inside the car or from the outside or station platform, and closed by power actuated mechanism, although in its broadest scope my invention is not to be limited or restricted in this respect since it is evident that a reversible motor with suitable control therefor might readily and easily be employed so as to secure power operation of the door for both its opening and closing movements.

In carrying out my invention I propose to provide a lock for locking each door in its closed position. One convenient arrangement for accomplishing this is to employ magnet controlled locking detents adapted to engage the doors when in their completely closed position and lock them in that position. When the lock controlling magnets are energized the locking detents are released from locking position. It is proposed, in accordance with my invention, to control the circuits of all the lock magnets from the same point or station, for instance, by means of switches located in the cab of the car or train motorman. In practice all the door lock magnets on each side of the car may be included in a single energizing circuit controlled by a single switch in the motorman's cab.

I also propose to employ a signal circuit which includes switches controlled by the various door lock magnets, whereby, when all the doors throughout the system are closed and locked, and not until then, the signal circuit is completed thereby indicating to the motorman that it is safe to start the train. If desired, and in a manner now well understood in the art, the completion of the signal circuit may be utilized to unlock or release or permit the operation of the train propelling motor control. I do not desire, therefore, to be limited or restricted in respect to the manner of utilizing the completion of the signal circuit in its relation to the operation of the train propelling motors.

I also propose, in accordance with my invention, to equip the front edge of each door with a safety shoe device so arranged as to yield towards the door in case the door, in its closing movements, encounters an obstruction, as well as when the door attains its final closed and locked position, by said shoe pressing against the door jamb.

I also provide the safety shoe with a handle by means of which said shoe may be collapsed or moved towards and relative to the door. And I utilize the movement of the safety shoe on each door towards and relative to the door, in whatever manner such movement is effected, to release or disconnect that particular door from its power actuated moving mechanism so that the door is no longer subject to the action of said power actuated moving mechanism and is free to be manually shoved or moved towards open position. As soon, however, as the encountered obstruction is removed, in case the safety shoe has been depressed by such an obstruction, and the shoe is permitted to return to its normal position relative to the edge of the door, the engagement to the power actuated mechanism is reestablished and the door resumes its closing movement. When the door attains its completely closed position the shoe is depressed by the door jamb, and the door is disconnected from its actuating mechanism and the door lock comes into action to securely lock the door against opening movement.

In the accompanying drawings I have shown a simple, practical and illustrative arrangement embodying the principles of my invention wherein I mount on each car of a train a single motor 6, see Fig. 1, to actuate all the doors of the car. The motor 6 drives a shaft 7, through suitable gearing 8, which shaft extends transversely across the car. It will be found convenient to locate the motor 6 and the shaft 7, at one end of the car and in the top of the car beneath the car roof. A sprocket wheel 9, is mounted on shaft 7 at each end thereof, and an endless sprocket chain 10, extends along each side of the car end engages over and is driven by the sprocket wheel 9, said chains operating over guide rollers 11 at the far end of the car, and, if desired, one or more intermediate idlers.

Each door 12, is supported by means of one or more suitably positioned rollers 13, operating upon a track 14, carried by the frame work of the car body. The door hanger rollers 13 are carried by bracket 15, secured to the door. Also carried by the bracket 15 is a sprocket wheel 16 to which is securely fastened a friction wheel 17. A friction brake device 18 is arranged to engage the friction wheel 17. A convenient arrangement is shown, to which, however, I do not desire to be limited or restricted, wherein the brake device 18 consists of two arms pivotally mounted upon the bracket 15 and disposed to partially embrace or clamp the periphery of the friction wheel 17 between them. A tension spring 19 connecting the free ends of said arms serves to yieldingly draw said ends together to cause said arms to exert a braking action on the

friction wheel 17. The free ends of the 5 brake device arms are connected by means of toggle connections indicated at 20, to a rod 21, which is carried by links 22, pivotally mounted at the front edge of the door, and disposed within the safety shoe device 23 in such relation that when the shoe 23 is collapsed upon or moved towards the door, the rod 21 is moved endwise upwardly and laterally towards the edge of the door thereby actuating the toggle connections 20, to 10 separate or force apart the free ends of the brake arms 18, thereby releasing the friction on friction wheel 17, and permitting the sprocket 16 to freely revolve. When the shoe 23 resumes its normally distended position the brake device is again applied and the sprocket wheel 16 is again locked against 15 rotation. Either the upper or the lower leg or run of the endless sprocket chain 10, depending upon the direction in which the door is to be moved, is made to engage the sprocket 16. When the sprocket wheel 16 is held against rotation by the application of 20 the brake device to the friction wheel 17, the actuating of the sprocket chain 10 by the motor 6 will cause the door to move to the right or to the left according to whether the one or the other leg or run of the endless 25 sprocket chain engages the sprocket wheel 16. Since it is a common practice to employ doors, such as centre-entrance doors, made in sections which move in relatively opposite directions, it will be seen that the arrangement above described is well adapted to such 30 practice. Similarly, it will be apparent that the doors at opposite ends of the car, while usually open in opposite directions, are also taken care of in this arrangement.

Each safety shoe device 23 is provided 35 with a handle 25 by means of which said shoe may be collapsed or depressed manually whenever desired to disconnect the door from its power driven actuating mechanism. When any door is disconnected from its 40 power driven actuating mechanism it may be easily and readily shoved or moved to open position by hand, unless it has been locked in its fully closed position, in which event it cannot be moved until the lock is released.

A simple arrangement of lock is shown in 45 Fig. 5, wherein a magnet 26, when energized, actuates a locking lever 27. This lever is so arranged as to engage behind the rear edge of the door when in its fully closed position, to prevent the door from being opened, said lever being normally pressed towards its locking position in any suitable or convenient manner, as by means of spring 28. The 50 circuit *a, b*, which includes the magnet also is to include, say, all the lock magnets on the same side of the car and is to be under the control of, for instance, the motorman. Each lock device also controls a switch 30

in a circuit *c, d*, in such manner as to close 55 said circuit at the lock device only when the lock lever is in locking position. This circuit may be called the signal circuit and it likewise contains a switch 30 which is controlled by each lock device, and also extends to the cab of the motorman to indicate, or control, when closed the proper or safe operation of the train propelling motors as 60 above explained. Of course it will be seen that this series signal circuit is not closed until all the doors are closed and locked. This is an important safety feature of my 65 invention.

The structure arrangement and operation 70 of the lock devices and their associated signal circuit controlling switches may be altered and varied throughout a wide range of details without departure from the spirit and scope of my invention. I do not desire, therefore, to be limited or restricted to the exact structure and arrangement 75 shown.

The operation of the apparatus is very 80 simple. When the train motorman stops his train at a station he closes the circuit of the locks for all the doors on that side of the car or cars which is adjacent the station or platform, thereby unlocking all the doors on that side but leaving all the doors 85 on the other side securely locked. Passengers desiring to enter or leave the car can then grasp the handle 25, one of which may be on the inside and another on the outside of the car, of any particular door 90 which may thereby be freely shifted or moved towards open position. After a pre-determined interval of time, say, for instance, fifteen seconds, the motorman will 95 close the circuit of all the motors 6, and at the same time open the circuit of all the lock magnets on the side of the train adjacent the station or platform. All doors which have been opened are thereupon 100 impelled by the power driven mechanism towards closed position.

If, in closing, any door strikes a passenger it is instantly disconnected from its power driven impelling means and can be easily and readily shoved 105 towards open position till the obstruction is removed and the shoe resumes its normal position, whereupon it will resume its power driven closing movement. When the doors are completely closed they are locked and 110 only when all of them are closed and locked the signal circuit is closed. The train may then be safely operated to proceed on its trip, and the motorman may then open the circuit of the motors 6.

Many adaptations, variations and changes 115 in details may readily occur to persons skilled in the art and still fall within the spirit and scope of my invention. I do not desire, therefore, to be limited or restricted 120 to the exact details shown and described.

For example, it will readily be understood that means may be provided, in conjunction with the system of my invention, for automatically opening and maintaining open the circuits of either or both the door locking magnets and the door motors, while the car is in motion. Such arrangements, and many others of similar nature and adaptability, are well recognized, and 10 are being used in the art, and per se form no part of my present invention.

Further, as above stated, many structural changes will readily suggest themselves to those skilled in the art. For example in Fig. 6 I have shown a greatly simplified arrangement wherein the door shoe, when collapsed, rocks a lever 40 one end of which is provided with sprocket teeth 44 yieldingly retained in mesh with the 20 sprocket chain 10, by a spring 45. The lever 40 is rotatively journaled at 42 in the bracket 15, and may engage either the upper or lower chain, according to which direction it is desired to move the door, as 25 clearly shown.

Further, if desired, and as shown as illustrative in Fig. 6, any desired number of rollers, idlers or the like 43 may be utilized for insuring proper connection between the 30 sprocket chain and the door actuator.

Further, I wish it to be understood that I do not desire to have the door lock circuit construed to apply to all doors on each side of the car or train but rather to all 35 doors, which are suitable for use at any certain station, for example, in interurban systems a train might have some doors for use with elevated platforms or stations and some doors opening onto steps where the station platform is on the level of the 40 ground. In such a system all the elevated doors on one side might have their locks included in one circuit, and all the doors with steps might have their locks on another circuit, and therefore only the doors 45 suitable for use at any predetermined type of station would be unlocked at any station stop. I therefore desire to have it understood that in the claims the expressions employed to define the plurality of doors are 50 employed with the purpose of including the foregoing arrangement as well as the others hereinbefore described unless otherwise specifically stated.

But having now set forth the objects and nature of my invention and an arrangement embodying the principles thereof, what I claim as new and useful, and of my own invention, and desire to secure by Letters 55 Patent, is,—

1. In a unit door control mechanism, the combination with a plurality of doors, of a single operating motor therefor, and means controlled by any door encountering an ob-

struction in closing for releasing said door 65 from its connection with said motor.

2. In a unit door control mechanism, a plurality of doors, a single motor, devices actuated thereby and common to all the doors for moving them, releasable connections intermediate each door and said motor actuated devices, and means carried by each door to control said releasable connections. 70

3. In a unit door control mechanism, a plurality of doors, a single motor, devices 75 actuated thereby and common to all the doors for moving them, releasable connections intermediate each door and said motor actuated devices, and means carried by each door to control said releasable connections. 80

4. In a unit door control mechanism, a plurality of doors, a single motor for operating all of them, a safety shoe mounted at the front edge of each door, and means operated by the movement towards the door of 85 the shoe on any door for releasing said door from its actuating connections with the motor without affecting the actuating connections of any other of the doors.

5. In a unit door control mechanism, a 90 plurality of doors, a single motor for operating all of them, a safety shoe mounted at the front edge of each door, and means operated by the movement towards the door of 95 the shoe on any door for releasing said door from its actuating connections with the motor without affecting the actuating connections of any other of the doors, and means for securing each door in its closed position. 100

6. In a unit door control mechanism, a plurality of doors, an actuating member operating past all of said doors, a single motor to drive said member, means carried by each door to engage said actuating member, and a safety shoe device carried by the free edge of each door and operating, when actuated towards the door, to release the engaging means of said door. 105

7. In a unit door control mechanism, a plurality of doors, an endless chain operating past all of said doors, a single motor to drive said chain, a movable member carried by each door and engaged by said chain, a brake device for said movable member, and a safety shoe at the front edge of each door, to control said brake device. 110

8. In a door control mechanism for cars, trains or the like, the combination with a plurality of doors, a door actuating motor, and unitary means controlled by said motor for actuating all of said doors on one side 115 of said car, train or the like.

9. In a door control mechanism for cars, trains or the like, the combination with a plurality of doors, a door actuating motor, and common means controlled by said motor for actuating all of said doors on one side 120 125

of said car train or the like to close the same.

10. In a door control mechanism for cars, trains or the like, the combination with a plurality of doors, a door actuating motor, means controlled by said motor for actuating all of said doors to close the same, and means for rendering said motor controlled means inoperative as to any door when such door in closing encounters an obstruction.

11. In a unit door control mechanism, the combination with a plurality of doors, of a single operating motor therefor, and means controlled by any door encountering an obstruction in closing for releasing said door from its connection with said motor and for automatically connecting said door with the motor when the obstruction has been removed.

20 12. In a door control mechanism, a door, an actuating motor, means controlled by said

motor for actuating the door, means for rendering said motor controlled means inoperative as to the door without affecting the operation of the motor when the door in closing encounters an obstruction, and means for again rendering the motor controlled means operative when the obstruction is removed.

13. In a door control mechanism, a door, an actuating motor, means controlled by said motor for actuating the door, a collapsible shoe carried on the front edge of the door, means for rendering said motor controlled means inoperative as to the door without affecting the operation of the motor when said shoe is collapsed, and means for again rendering the motor controlled means operative when the shoe is again extended.

In testimony whereof I have hereunto set my hand on this 1st day of June A. D. 1921.

HAROLD ROWNTREE.
